UNITED STATES PATENT OFFICE.

WILLIAM BORCHERT AND FRED L. BORCHERT, OF ROCKFORD, ILLINOIS, ASSIGNORS TO THE TAGIT COMPANY, OF ROCKFORD, ILLINOIS, A CORPORATION OF ILLINOIS.

TAG-AFFIXING MACHINE.

Application filed October 29, 1920. Serial No. 420,420.

To all whom it may concern:

Be it known that we, WILLIAM BORCHERT and FRED L. BORCHERT, citizens of the United States, residing at Rockford, in the county of Winnebago and State of Illinois, have invented certain new and useful Improvements in Tag-Affixing Machines, of which the following is a specification.

This invention pertains to machines or devices for affixing tags to flat material, and has more particular reference to that class especially adapted for affixing laundry tags.

The primary object of this invention is to provide a simple and novel hand-operated device for affixing tags, preferably of the U-shaped type, to flat material, which machine shall comprise but a minimum number of parts and shall be so constructed as to enable production at a very low cost.

Another object is to provide a tag-affixing machine of the character described of such novel design as to enable shipment in a knock-down condition in a small compact bundle.

Another important object is to provide an affixing machine including an anvil and a hammer or maul permanently suspended thereabove and adapted to be freely manipulated to strike a tag positioned on the anvil for clamping such tag to the goods. In this regard, we have also aimed to so shape the faces of the anvil and maul as to prevent cutting of the goods by striking contact of the maul and anvil faces.

Still another object is to provide a base which shall serve as a container for the disassembled parts when shipping, and a substantial base for the anvil, maul and other parts when in operative condition.

Other objects and attendant advantages will be appreciated as the invention becomes better understood by reference to the following description when considered in connection with the accompanying drawing, in which—

Figure 1 is a perspective view of a tag-affixing machine embodying our invention;

Fig. 2, a fragmentary vertical sectional view through the machine showing the maul in an operated position;

Fig. 3, a top view of the base and parts in disassembled position therein for shipment; and

Fig. 4, a perspective view of a U-shaped

tag adapted to be affixed by the present machine.

The base designated generally by character 5, in the form of a rectangular open-top box, is preferably cast to shape so as to have sufficient weight. A partition 6 divides the base into compartments 7 and 8, the latter of which holds the tags in loose condition. This compartment 8 is also of requisite size to hold a paper container or box of tags in a convenient and readily accessible position.

The anvil 9 having downwardly diverging legs 11 integral therewith, is detachably mounted on the base, it being observed that the legs terminate in angular feet 12 which fit the inner corners of the base and seat upon the top edge thereof and are clamped to the base by screws 13. The rear portion 14 of the anvil face is raised slightly above the active clamping face 15 for a purpose presently to be described.

A hammer or maul having an enlarged flat head 16 and a handle 17 is suspended above and in alignment with the anvil by means of a contractile spring 18 and a supporting rod 19, the latter of which being of a general U-shape as shown, is detachably secured at its lower end in a socket in the anvil by a screw 21.

As shown in Fig. 1, the maul is normally suspended above the anvil. The tag 22 to be affixed to the goods 23 will be placed over the edge thereof and positioned anywhere on the face of the anvil. It might be mentioned that either a U-shape or V-shape tag might be affixed to the goods with this machine. These tags having inwardly pointed spurs which pierce the goods for insuring a good hold thereon, are well known to the laundry trade. With the tag and goods so positioned and held on the anvil by one hand, the operator with the other hand grasping the handle 17, drives the maul down with a quick forcible blow so as to strike the tag and clamp it to the goods.

It will be observed that in this action the face of the maul strikes both the tag and the raised face 14 of the anvil. This face 14 prevents the maul from striking the goods and consequently cutting or marring the same as would result if in the absence of such face 14 the maul did not hit the tag squarely and would strike the goods. It

follows, therefore, that we have provided means independent of guides or other extraneous devices for positively insuring that the tag will be properly engaged and clamped by the maul without injury to the goods.

It will be further observed that the parts above described are so shaped and constructed as to be capable of arrangement when 10 disassembled in the manner shown in Fig. 3. That is, the anvil as one unit and the maul, spring and supporting rod as another unit, may be positioned within the base, with the anvil, maul and spring in the tag 15 compartment 8 and the supporting rod extending diagonally across the top of the base with its ends extending down into the corners of the base. Thus, the parts may be very compactly arranged in a small bundle for shipping.

It is believed that the foregoing conveys a clear understanding of the objects prefaced above, and while we have described but a single working embodiment of our 25 invention, it should be understood that various changes might be made in the construction and arrangement without departing from the spirit and scope of the invention as expressed in the appended claims, in 30 which—

We claim:

1. A tag-affixing machine of the character described, comprising a base shaped to provide an open-top receptacle for tags, an anvil rigid on the base, an upstanding support 35 terminating at a point above and in vertical alignment with the anvil, a coil spring attached to and depending from the upper end of said support, and a maul attached 40 to and depending from said spring in vertical alignment with the anvil and adapted to be manually depressed for striking a U-shaped tag positioned on the anvil for clamping said tag to a piece of flat material.

2. A tag-affixing machine of the character described comprising a base shaped to provide at its front end an open-top tag receptacle, an anvil rigidly supported on the back portion of said base, an upstanding support rigid with respect to the base and 50 terminating above the anvil, and a maul yieldingly supported from the upper end of said support in vertical alignment with the anvil and having at its lower end an enlarged head and at its upper end a handle 55 adapted to be grasped for striking the head against the anvil and clamping an interposed U-shaped tag or the like to a piece of flat material.

3. In a tag-affixing machine, the combination of a rectangular box-like base, an anvil having diverging legs detachably secured to the corners at one end of the base, an upstanding rod detachably secured to the anvil, a contractile spring attached to the upper end of the rod, and a maul attached to the spring and suspended above the anvil.

4. In a tag-affixing machine, the combination of a rectangular box-like base constituting a tag receptacle, an anvil mounted on the base and adapted to be moved from operative position and placed within the base, a maul, and means supporting the maul above and in alignment with the anvil, said maul being removable from operative 75 position and adapted to be positioned within the base for purpose of shipment.

5. A tag-affixing machine comprising a base having an anvil, an upstanding support, a pendent contractile spring above the 80 anvil attached to the support, and a maul attached to the lower end of the spring and normally suspended above and in alignment with the anvil, the maul adapted to be grasped by hand and moved downwardly 85 for striking a tag positioned on the anvil.

WILLIAM BORCHERT.
FRED L. BORCHERT.
